UNITED STATES PATENT OFFICE.

JAMES BURRIS, OF HOPKINSVILLE, KENTUCKY.

SAFETY ENVELOPE.

Application filed September 23, 1924. Serial No. 739,338.

To all whom it may concern:

Be it known that I, JAMES BURRIS, a citizen of the United States, residing at Hopkinsville, in the county of Christian and 5 State of Kentucky, have invented certain new and useful Improvements in Safety Envelopes; and I do hereby declare the following to be a full, clear, and exact description of the invention, such as will enable 10 others skilled in the art to which it appertains to make and use the same.

The present invention provides an envelope which when closed may be sealed without using an adhesive or other additional fastening means except those self contained within the article, and such envelope when sealed may not be opened without making detection possible because of mutilation of the closure.

20 Other objects and advantages will be apparent and suggest themselves as the nature of the invention is understood.

While the drawings illustrate an embodiment of the invention it is to be understood 25 that in adapting the same to meet different conditions and requirements, various changes in the form, proportion and minor details of construction may be resorted to without departing from the nature of the 30 invention.

Referring to the accompanying drawing forming a part of the specification,

Figure 1 is a rear view of an envelope embodying the invention as it appears when 35 sealed,

Figure 2 is a detail view of the envelope partly open, and

Figures 3 and 4 are detail views.

Corresponding and like parts are referred 40 to in the following description and designated in the several views of the drawing by like reference characters.

The envelope comprises two parts a blank which when folded forms the envelope and 45 a strip forming the connecting means between opposite ends and a bottom flap.

The body of the envelope consists of a blank of paper adapted to have its four corner portions inwardly folded whereby to 50 provide a front 1 opposite end flaps 2 and 3

and side, or top and bottom flaps 4 and 5, respectively. The end flaps 2 and 3 overlap and each is formed with a slit 6. A strip 7, of paper or other suitable material, has lateral cuts 8 in opposite edge portions adjacent its ends and the part of the strip 7 beyond the lateral cuts 8 are adapted to be folded so as to pass through the slits 6 after which they are extended to prevent withdrawal of the ends of the strip 7 through the slits 6. The strip 7 serves to connect the end flaps 2 and 3 and is formed with a longitudinal slit 9 which registers with corresponding slits 10 in the end portions of the flaps 2 and 3 and which registering slits 9 and 10 receive the end of the bottom flap 5 and which end has opposed lateral cuts 11 which enables edge portions of the flap 5 to be folded so that the end may be passed through the slits 9 and 10 after which the parts are extended to prevent the withdrawal of the end of the flap 5 through the slits 9 and 10. The bottom flap 5 is formed with a slit 12 which is adapted to receive the end of the top flap 4 and which end has opposed lateral cuts 13 which enable edge portions of the flap 4 to be folded so that its end may pass readily through the slit 12 after which the folded edge portions are extended to prevent withdrawal of the end of the flap 4 through the slit 12.

It will be understood from the foregoing that the invention provides an envelope which may be made secure and sealed without the use of an adhesive and which when closed and sealed may not be opened without mutilating the article to such an extent as to render detection possible.

What is claimed is:

An envelope having opposite end flaps overlapped and provided with slits, a top flap, and a bottom flap, a strip having opposed lateral cuts adjacent its ends to admit of edge portions being folded and insertible through the slits of the flap and subsequently extended to prevent withdrawal of the ends of the strips through the receiving slits, the said strip and the overlapping end portions of the flap having registering slits to receive the end of the

bottom flap, said end having opposed lateral cuts to admit of edge portions being folded and the end of the flap passed through the registering slits after which said edge portions are extended to fold the end of the flap from withdrawal, the bottom flap having a slit to receive the end portion of the top flap

which is provided with opposed lateral cuts to admit of edge portions of the end of said top flap passing through the slit of the bottom flap and subsequently extended to prevent separation of the parts. ¹⁰

In testimony whereof I affix my signature.

JAMES BURRIS.
